US00D888752S

(12) **United States Design Patent** (10) Patent No.: **US D888,752 S**
(45) Date of Patent: **** Jun. 30, 2020**

(54) **DISPLAY SCREEN WITH GRAPHICAL USER INTERFACE**

(71) Applicant: **LG ELECTRONICS INC.**, Seoul (KR)

(72) Inventors: **Youngjin Kang**, Seoul (KR); **Eunbin Kim**, Seoul (KR); **Mijun Yoo**, Seoul (KR); **Byoungnam Lee**, Seoul (KR); **Inseong Cho**, Seoul (KR)

(73) Assignee: **LG Electronics Inc.**, Seoul (KR)

(**) Term: **15 Years**

(21) Appl. No.: **35/506,510**

(22) Filed: **Aug. 9, 2018**

(80) **Hague Agreement Data**

Int. Filing Date: **Aug. 9, 2018**

Int. Reg. No.: **DM/102649**

Int. Reg. Date: **Aug. 9, 2018**

Int. Reg. Pub. Date: **Feb. 15, 2019**

(30) **Foreign Application Priority Data**

Feb. 9, 2018 (KR) 30-2018-0007277

(51) **LOC (12) Cl.** **14-04**

(52) **U.S. Cl.**

USPC **D14/486**

(58) **Field of Classification Search**

USPC D14/485-495
